UNITED STATES PATENT OFFICE.

HAROLD G. SCHLECHT, OF BRADENTOWN, FLORIDA.

SPARK PLUG.

Application filed February 14, 1920. Serial No. 358,628.

To all whom it may concern:

Be it known that I, HAROLD G. SCHLECHT, a citizen of the United States, residing at Bradenton, in the county of Manatee and 5 State of Florida, have invented new and useful Improvements in Spark Plugs, of which the following is a specification.

This invention relates to spark plugs for internal combustion engines and has for its 10 object the provision of a spark plug in which one electrode is movable with respect to the other while remaining always at a constant distance therefrom and movable at every explosion within the cylinder, 15 whereby the formation of an oil bridge between the electrodes will be prevented and whereby a short circuiting caused by an accumulation of carbon between the electrodes will also be prevented.

20 An important and more specific object is the provision of a spark plug of this character in which is provided a metal disk slidably mounted upon the central electrode and movable within the hollow body of the plug, 25 the disk engaging and closing the end of the skirt of the porcelain insulator at every explosion in the cylinder.

An additional object is the provision of a 30 plug of this character which will be simple and inexpensive in manufacture, highly efficient in use, durable and long lived in service, and a general improvement in the art.

With the above and other objects and advantages in view, the invention consists in 35 the details of construction to be hereinafter more fully described and claimed, and illustrated in the accompanying drawings in which

Figure 1 is a longitudinal sectional view 40 through my improved plug, and

Figure 2 is a cross sectional view therethrough.

Referring more particularly to the drawings, the letter A designates the body of the 45 plug which is formed of metal and which is of ordinary construction and which has the lower end of its bore B of uniform diameter. The letter C designates the porcelain insulator having the usual depending skirt 50 D and through which extends the central electrode E.

In carrying out my invention I provide a metal washer or disk 10 which has a central hole and which is slidably engaged upon the 55 electrode E, the latter having its extremity upset or lifted, as shown at 11, whereby to

provide retaining means to prevent the disk from slipping off. This disk has a diameter one sixteenth of an inch less than the internal diameter of the bore B so that there 60 will be provided a continuous spark gap one thirty-second of an inch between the periphery of the disk 10 and the inner wall of the bore B, it being well known that one thirty-second of an inch is the most desirable 65 length spark gap.

In the operation of my plug it will be seen that it will be impossible for a drop of oil to remain in bridging relation to the disk and plug as at every explosion in the cylinder 70 the disk will be forced along the electrode E. During the compression stroke in the cylinder there will be no movement in the disk as the pressure on both sides will be equal but the explosion being sudden will cause 75 movement of the disk. It will be seen that regardless of the position of the disk along the electrode E, the proper spark gap will always be provided. It will also be apparent that it will be impossible for carbon to 80 accumulate within the bore of the plug or to get into the skirt of the porcelain insulator as this skirt is closed by the disk at each explosion and as the disk slides within the bore continually. 85

While I have shown and described the preferred embodiment of my invention, it is of course to be understood that I reserve the right to make such changes in the form, construction, and arrangement of parts as 90 will not depart from the spirit of the invention or the scope of the subjoined claims.

Having thus described my invention, I claim:

1. In a spark plug, a metallic shell, a main 95 electrode rod having its cylinder end surrounded by the corresponding end of the shell, and a disk slidably mounted on the cylinder end of the rod and having its edge located adjacent to the wall of the shell to 100 produce a spark gap between said edge and wall.

2. In a spark plug, a metallic shell, a main electrode rod having its cylinder end surrounded by the corresponding end of the shell 105 and a plate slidably mounted on the cylinder end of the rod and having its edge located adjacent the wall of the shell to produce a spark gap between said edge and wall.

In testimony whereof I affix my signature. 110

HAROLD G. SCHLECHT.
